UNITED STATES PATENT OFFICE.

GEO. W. WILSON AND A. JOHNSON, OF WALNUT GROVE, ILLINOIS.

WASHING-MACHINE.

Specification of Letters Patent No. 22,761, dated January 25, 1859.

To all whom it may concern:

Be it known that we, **GEORGE W. WILSON** and **A. JOHNSON**, of Walnut Grove, in the county of Knox and State of Illinois, have 5 invented a new and Improved Clothes-Washing Machine; and we do hereby declare that the following is a full, clear, and exact description of the same, reference being had to the annexed drawings, making 10 a part of this specification, in which—

Figure 1, is a longitudinal and vertical central section of our invention. Fig. 2, is a vertical transverse section of do, taken in the line *x*, *x*, Fig. 1.

15 Similar letters of reference indicate corresponding parts in the two figures.

To enable those skilled in the art to fully understand and construct our invention we will proceed to describe it.

20 *A*, represents a box or case, one part *a*, of which is provided with a cover *B*, which is hinged to the box as shown at *b*. This box or case may be constructed of wood and within the part *a*, of the box *A*, a cylinder *C*, is placed, said cylinder being formed of a series of slats *c*, and perforated strips *c'* attached to heads *d*, *d*, placed on a proper shaft *e*. The slats *c*, externally are of semi-cylindrical form as shown clearly in Fig. 1. 25 A section of the periphery of the cylinder *C*, is open as shown at *f*, and a plate *g*, is fitted therein, said plate being attached to the ends of arms *h*, *h*, which are attached, one to the inner side of each head *d*. Through the 30 arms *h*, *h*, a screw rod *i*, passes, said rod also passing through curved slots *j*, in the heads *d*, *d*, the rod having a head *k*, on one end and a thumb nut *l*, on the other, see Fig. 2.

In the upper part of the cover *B*, a rubbing device *D*, is placed. This device is 35 formed of a slat *m*, placed transversely in the upper part of the cover and covered with cloth *n*, or an elastic and soft material. At each side of the slat *m*, and parallel with it a series of slats *o*, are secured. These slats 40 may be of metal or wood. If constructed of metal, sheet metal plates may be bent or crimped so as to form corrugations parallel with the slat *m*. If the slats are of wood 45 they may be of similar or an approximate form made separately of course and then attached to the cover in the same position as the metal ones, at the ends of each series of slats *o*, a roller *p*, is placed, the journals of 50 the rollers being fitted in yielding bearings.

The slats and rollers extend the whole width of the cover *B*, and the rubber as a whole has a curved form corresponding to the curvature of the cylinder *C*, as plainly shown in Fig. 1.

60 The bottom of the part *a*, of the box *A*, is curved as shown in Fig. 1, and a frame *E*, is placed on said bottom the frame being also curved and resting at its ends on springs *q*. To the sides of the part *a* of the box *A*, 65 vertical guides *r*, are attached, said guides fitting in recesses in the sides of the frame *E*, and serving to keep the same in proper position. At the center of the frame *E*, a roller *s*, is placed.

70 The operation is as follows:—The clothes to be washed, shown in red are secured to the external surface of the cylinder *C*, by means of the plate *g*, which is secured in proper position by the rod *i*. The part *a*, of the box *A*, is supplied with a requisite quantity of 75 suds, and the cylinder *C*, is rotated by hand or by any proper means, the clothes are carried around on the cylinder *C*, saturated as they pass through the suds and are rubbed 80 by the rubber *D*. The roller *s*, expresses the dirt from the clothes that is loosened by the rubber, the pressure of the roller being governed by the springs *q*. It will be seen that the clothes are not subjected to friction while in the water as the rubber is 85 placed over the cylinder, the rubbing being done when they are out of the water. It will also be seen that by turning the cylinder first in one direction and then in the other 90 both sides of the clothes may be washed as the clothes will be reversed on the cylinder by the change of motion.

Having described our invention, we claim and desire to secure by Letters Patent,

95 As an improved article of manufacture, a washing-machine having upon the central cylinder *C*, a plate (*g*) arms (*h*, *h*), curved slots (*j*), and rod (*i*) for securing the clothes, and in the upper part of the cover *B*, a rubbing device *D*, consisting of a slat (*m*) with slats or corrugations (*o*) at its sides, and rollers (*p*), and otherwise constructed as herein shown and described.

100 **GEORGE W. WILSON.**
ANDREW JOHNSON.
